[57] CLAIM

The ornamental design for a telephone, as shown and described.

DESCRIPTION

FIG. 1 is a side view in perspective showing my new design;

FIG. 2 is a top view in perspective of said design;

FIG. 3 is a side view in plan; and

FIG. 4 is a rear view in plan.

The characteristic features of my design reside in the specific configuration of the push button panel in combination with a conventional telephone set.
